UNITED STATES PATENT OFFICE.

ANDREW M. EASTMAN, OF SOMERVILLE, ASSIGNOR TO THE TUCKER MANUFACTURING COMPANY, OF BOSTON, MASSACHUSETTS.

SPRING-BED.

SPECIFICATION forming part of Letters Patent No. 248,296, dated October 18, 1881.

Application filed July 18, 1881. (No model.)

To all whom it may concern:

Be it known that I, ANDREW M. EASTMAN, of Somerville, county of Middlesex, State of Massachusetts, have invented an Improvement in Spring-Beds, of which the following description, in connection with the accompanying drawings, is a specification.

This invention in spring-beds relates to a novel method of supporting the slats in sets of three by means of but two springs. The three slats are joined together by means of a slat-connecting wire, which holds them at the proper distance apart, the hooked ends of the two springs engage the said wire between adjacent slats, and the compound slats, composed each of three slats, are connected together by means of suitable hooks and eyes.

Figure 1 represents in top view a spring-bed embodying my invention; Fig. 2, an end view thereof, and Fig. 3 a detail in side view of one of the springs.

The sides *a* of the bed-frame are held together by the cross-bars *b*, which latter are provided with suitable wire-bearing loops, *b'*, which receive and support the spring-holder *c*, made as a metal rod.

The springs *d e*, employed in pairs, are made from wire bent as shown. The short arm of each spring enters a suitable hole in the cross-bar *b*, while its long arm is made into a hook, as shown in Fig. 3, to engage the slat-connecting wire *g*, which latter is of sufficient length to extend through the separate slats 2 3 4 of each compound slat *f*. Each compound slat is composed of three slats united by the said connecting-wire extended loosely through them, the several compound slats to form a bed being joined together by eyes or loops *h*. The connecting-wire *g*, when inserted through the central slat, 3, is straight; but thereafter it will be bent at each side of the slat 3, to form cranks, as shown in the drawings, to prevent lateral displacement of the slats, with which

cranks the hooked ends of each pair of springs *d e* are connected and held, as shown, the connection of the said springs with the wire *g* being only between the slats 2 3 and 3 4, so that two springs at each end of the bed-frame are made sufficient to support both ends of the three slats united to form a compound slat. 45 50

The springs and spring-holders *c* are commonly used in spring-beds. Making two springs at each end of the frame answer for three slats enables the construction of the bed-bottom to be cheapened, and joining the three 55 slats into one by a rigid connection is found to be of advantage, improving the comfort of the person supported thereby.

The eyes permit the slat bottom to be folded compactly for shipping or storage. 60

With a compound slat composed of four slats I might use three springs at each end.

I claim—

1. A spring bed composed of a number of compound slats, *f*, each composed of three slats, 65 which are united by a cranked connecting-wire, *g*, the several compound slats being also connected, combined with two springs at each end of each compound slat, and engaging with the said connecting-wires, so as to present at 70 the end of each compound slat fewer springs than there are separate slats in said compound slats, substantially as described.

2. A series of compound slats, *f*, composed each of three slats, 2 3 4, united together by 75 the connecting-wires *g*, cranked, as shown, combined with two springs at one or both ends of each compound slat, and with connecting devices *h*, substantially as described.

In testimony whereof I have signed my name 80 to this specification in the presence of two subscribing witnesses.

ANDREW M. EASTMAN.
